(57) CLAIM

The ornamental design for a sports training net, as shown and described.

DESCRIPTION

FIG. 1 illustrates a perspective view of a first embodiment of a sports training net;

FIG. 2 illustrates a front view thereof;

FIG. 3 illustrates a rear view thereof;

FIG. 4 illustrates a side view thereof in which the front side is facing the right and the rear side is facing the left;

FIG. 5 illustrates a side view thereof in which the front side is facing the left and the rear side is facing the right;

FIG. 6 illustrates a top view thereof;

FIG. 7 illustrates a bottom view thereof;

FIG. 8 illustrates a perspective view of a second embodiment of the sports training net;

FIG. 9 illustrates a front view thereof;

FIG. 10 illustrates a rear view thereof;

FIG. 11 illustrates a side view thereof in which the front side is facing the right and the rear side is facing the left;

FIG. 12 illustrates a side view thereof in which the front side is facing the left and the rear side is facing the right;

FIG. 13 illustrates a top view thereof;

FIG. 14 illustrates a bottom view thereof;

FIG. 15 illustrates a perspective view of a third embodiment of the sports training net;

FIG. 16 illustrates a front view thereof;

FIG. 17 illustrates a rear view thereof;

FIG. 18 illustrates a side view thereof in which the front side is facing the right and the rear side is facing the left;

FIG. 19 illustrates a side view thereof in which the front side is facing the left and the rear side is facing the right;

FIG. 20 illustrates a top view thereof; and,

FIG. 21 illustrates a bottom view thereof.

The broken lines shown in the drawings depict environment and form no part of the claimed design.
